SHUTTLE FOR BADMINTON AND THE LIKE

Addison T. Saunders, Akron, Ohio, assignor to
A. G. Spaulding & Bros., New York, N. Y., a
Corporation of New Jersey

Application January 26, 1931. Serial No. 511,423

22 Claims. (Cl. 273—106)

My present invention relates to improvements in a shuttle for the games of badminton, battledore and shuttlecock or the like, and also relates to a method of producing the improved shuttle.

5 An object of the invention is to provide a seamless, featherless, flight controlling vane for the shuttle, which vane is circumferentially uniform and symmetrical, and to provide an effective method for producing the same.

10 Another object is the provision of a shuttle having a relatively inexpensive, strong, durable envelope of novel character for the head thereof to substitute the usual white kid leather covering or envelope.

15 A further object is to provide a vane for the shuttle which is strong and durable while possessing graduated stiffness and terminal yieldability or resilience as in the usual feathered vane.

20 Another object is the provision of a shuttle for the games of badminton, battledore and shuttlecock, which while possessing all the qualities of the known shuttles which ordinarily are provided with an assembly of feathers as a flight controlling vane, will be featherless, but will have combined with the head portion a flight controlling vane, of a more simple and less costly form, both as regards its manufacture and as regards its assembly with said head, said vane being clearly visible in flight and as pleasing to the eye as the feathered form.

25 The invention further aims to provide as a means to take the place of the feathers a form of flight controlling vane which will simulate the control exerted by feathers, as ordinarily employed, at all stages of the game. That is, not only when the shuttle is in full flight will this simulation in action take place, but throughout 30 the whole period of play, including the moment at which the shuttle is struck and started on its flight, during the main part of its flight, and its action of turning downwardly quickly, head foremost, when the momentum is spent.

35 The invention consists in the features of construction and method of production of the article as hereinafter described and pointed out particularly in the claims.

40 In the drawing showing an embodiment of my invention and illustrating my method of making the shuttle,

45 Figure 1 is a view showing the formation of the vane portion of the shuttle.

50 Fig. 2 shows the vane after removal from the

cone-shaped form and prior to its attachment to the head shown in cross-section in Fig. 3.

Fig. 4 shows the finished shuttle.

Fig. 5 is a view of another form of vane, on reduced scale.

Fig. 6 is a view of still another form of vane. 60

Fig. 7 is an end view of the vane of Fig. 5.

Fig. 8 is an end view of the vane of Fig. 6.

Fig. 9 shows a form of covering for the head reinforced with fabric material. 65

The drawing is diagrammatic and illustrates the features of the present invention independently of exact sizes or proportions, it being understood that the improvements are to be applied in making shuttles of regulation sizes and proportions. The sizes and proportions shown in the drawing are approximations only. 70

Referring to the drawing, Fig. 4 shows a completed shuttlecock embodying and made according to my invention, in which I provide a cone-shaped vane member 1 of seamless tubular fabric 75 the smaller end of which is secured to the base or butt end 5b of the head 5 which is preferably of cork as in the ordinary shuttle, or cork aggregate, and which I provide with a colloidal or colloidal composition envelope or covering 5a 80 to substitute the usual leather covering. The white kid leather usually employed is expensive and a material saving is had by employing my substitute envelope. This colloidal envelope 85 comprises colloidal materials such as rubber, plasticized glue, or plasticized pyroxylin. In employing any of these I incorporate a white pigment such as the sulphide or oxide of zinc or oxide of titanium. By right pigmentation 90 and thickness of the envelope I obtain such weight as may be desired to secure the required weight of the shuttle head.

A feature of my improved featherless cone-shaped vane member, is that it is of seamless 95 tubular fabric which, in the ultimate cone-shape which I impart to it, is of itself heavier and more dense per unit of surface area near the smaller end of the cone, where it joins the base or butt of the head 5, than toward the larger end of 100 the cone.

This I accomplish in a tubular textile fabric by providing large spaces between the strands toward the larger end of the cone while providing smaller spaces between the strands near the 105 smaller end of the cone, according to my method hereinafter described.

This produces a gradual change in weight per unit of surface area due to change in density of texture of the fabric itself from the large end 110

of the cone and increasing toward the small end, as in the known feathered vane.

The cone-shaped tubular fabric is held in such condition by a stiffening material or coating applied to the entire cone of fabric. In the textile fabric, the fibres, threads, or strands are fixed or rigidified in the relatively open mesh condition toward the large end of the cone and in the relatively close mesh condition near the smaller end of the cone.

The greater heaviness or density when the fabric cone is stiffened from end to end by the coating, results of itself in gradual increase in strength or stiffness of the cone toward the small end independent of variations in stiffness imparted by application of coating in greater quantity at one point than at another. This is due to the increasingly greater number of stiffened or rigidified strands per unit of area toward the smaller end.

The stiffening material which is applied to the entire surface of the cone and which serves to stiffen, rigidify, or fix the strands or fibres of the seamless tubular textile fabric in the cone shaped conditions described, is preferably used in greater amount near the smaller end of the cone than toward the larger end thereof, which augments the initial variation in strength, stiffness, and weight, resulting from simply applying stiffening coating to the entire cone as it gradually varies from open mesh to close mesh toward the small end.

In carrying out my invention, I proceed substantially as follows. Over a cone-like form of duralumin—this metal being preferably chosen for its low gravity and consequent convenience in handling, and for its property of resisting adhesion of glue and the like, I draw a seamless tube preferably knitted from a fine thread, preferably silk. By experimentation I have secured a knitted tube of a size and degree of stretch and adaptation that, while it can be stretched over the larger end of a form representing the dimensions of the larger end of the vane (about 2 1/2"), it will contract and fit smoothly the smaller end of this tapered form (about 7/8"), when stretched longitudinally.

Fig. 1 illustrates such a cone as described, one end of a section of the seamless tubing, 1, being firmly held about the shank of the cone by a rubber band, 2, and the opposite end of the section being drawn taut over the smaller end of the cone and held there by the cord tied about it at 3.

The progressive expanding of the tube toward the larger end of the cone and its compacting toward the smaller end makes the larger end much lighter per unit of area than the other part, and this thinning from stretch aids in securing equilibrium by the location of center of gravity at the base 5b of the cork head, the entire cone of fabric being stiffened, fixed, or rigidified by application of coating thereto. The more compact condition of the stiffened fabric at the small end (representing the quill portion of the feathered vane), is further strengthened by heavier treatment with the stiffening material, which is important since it must bear the greater part of the shock of impacts upon the nose 5c of the cork head.

A section of this tubing having been drawn over the form as shown and described, the stiffening material, preferably plasticized glue or pyroxylin, with which is incorporated sulphide or oxide of zinc or oxide of titanium, or the like,

for whiteness, is applied by dipping, or brushing on. And the stiffening is increased progressively from the larger end of the vane to the smaller by either of two methods of applying.

According to one method I first dip the vane for its entire length in a thin solution of the stiffening material, then for less than its entire length, small end first, and in a vertical position in a preferably thicker solution keeping the larger end above the surface of the second solution, immersing a still less part of the entire length in a still thicker solution, performing this dipping in as many steps as may be required for graduation without abruptness. I find four steps produce an apparent continuous increase in thickness of coating with all desired lightness at the large end of the vane and of strength at the small end, these dips being performed without permitting drying between them. I do not limit myself to any particular number of dipping steps.

When a quick-drying solution, such as pyroxylin in a suitable solvent such as butyl-acetate is used, the above effect of graduation of thickness of coating can be had by a gradual and properly timed withdrawing of the vane, with one single solution. According to this method the thickness of the coating is directly affected by the rate of withdrawal of the part leaving the surface of the solution at any time. This is due to the alteration in the rate of evaporation of the solvent.

When a glue compound is used for stiffening the vane I may treat the same, after coating, with formaldehyde or its equivalent, to render it moisture-proof.

While the stiffening materials employed strip freely from the duralumin form, the white pigments employed therewith have a tendency to cause adhesion. I, therefore, preferably lubricate the cone before stretching on the knitted material. For a glue compound a film of paraffin, applied in solution or rubbed on, is used, and when a pyroxylin compound is used—a film of soap is applied.

When the stiffening coats are dry the cone of silk is readily removable from the form. This is best done by cutting around the sharp angles of both ends with a sharp trimming knife, the form of the duralumin cone enabling this, and its length being that required for the vane. When this is neatly done the vane is ready for mounting on the head. It is easily drawn from the form and is shown in Fig. 2.

The withdrawing of the pyroxylin-stiffened vane is facilitated by dipping in hot water or by steaming, which causes it to slip from the soap or other lubricant film.

The smaller end of the vane is formed of a size calculated to enable it to be fitted around the shank 5b of the cork head shown in Fig. 3. In this figure 5 represents the rounded portion of the head beyond the shank 5b, the head 5 being covered with the envelope 5a which I substitute for the kid, as described above. The cork portion may be the natural cork or ground cork mixed with a suitable binding material. This envelope is of a colloidal or colloidal composition material, which I plasticize to any desired degree with known softeners such as glycerine or sulphonated castor oil for the glue mixture, and sulphonated castor oil or dibutylphthalate or the like for a pyroxylin mixture. When rubber is used for the envelope no plasticizing is required. I prefer to form this envelope by dipping the

cork head in a solution, of the material chosen, pigmented as hereinbefore described. Those skilled in the arts will understand that after dipping, inverting of the head at a certain optimum time while drying will insure an even forming of the envelope. An alternative method is to mould the envelope from these materials and cement it on to the cork head with cement of the same base as the colloid.

- 5 10 I may reinforce the colloidal envelope by admixture of fibre, as of silk, or by a fabric such as the knitted material of the vane. This material has the characteristic of stockinet, being susceptible to drawing over the head or a like 15 form smoothly and without fold or wrinkle. An envelope formed of this material and impregnated with a colloidal material such as described for the envelope, is strengthened against mutilation in play. Such an envelope is shown applied 20 to the cork head in Fig. 9.

My invention contemplates in addition to the plain colloidal envelope a colloidal composition envelope for the cork head, comprising a suitable base or filler impregnated or bound together 25 with colloids, such as above set forth, to substitute the usual kid leather envelope. The base material may as above stated, include fibrous material, such as silk, or a fabric material.

- Or it may comprise paper or paper pulp, felted 30 hair or other fibrous material. This material may comprise any of the materials named, alone or in combination, in a comminuted state or otherwise, and to this material is added the binder comprising the colloids mentioned, such 35 as plasticized glue, pyroxylin, rubber, or the like, to form a yielding covering for the cork head having the necessary degree of strength, wear, weight, and general behavior, as a practical substitute for the ordinary and expensive kid 40 leather envelope.

In attaching the vane to the head, the lower portion of the former, a narrow rim, is first softened, with water in the case of glue, and if of pyroxylin by the vehicle used in reducing it 45 to solution, or a similar solvent. In this softened state the rim of the vane is easily adjusted around the shank 5b of the head and glued or cemented thereto. The shuttle is finished by trimming with the usual band of ribbon, shown 50 at 4, Fig. 4.

While the plain non-fluted vane is desirable, I find that a fluting of the larger end of the vane has certain advantages with respect to increased air resistance and tendency to maintain symmetry. Two somewhat similar forms of this fluting are shown in Figs. 5, 6, 7, and 8. Figs. 5 and 6 show these in perspective while Figs. 7 and 8 represent plan views of the upper edge of vanes fluted in these forms. Both of these types of fluting consist of a series of V-shaped prominences, as seen from without, or V-shaped grooves when viewed from within. The flutings in each case should preferably be sixteen in number, corresponding with the usual sixteen feathers in the ordinary shuttle. These V's are of equal size and are disposed contiguously about the periphery of the large end of the vane in saw-tooth or zig-zag fashion. These flutings may, if desired, extend well down the body of the vane, but in the drawing I prefer to show them as I now prefer to use them, tapering down to nothing at a short distance from the large end of the conical vane, growing narrower and shallower in straight lines a and b until they merge into the level smooth surface

of the vane as indicated at the points c which are annularly in line. The ridges of the V's are shown at d. The corresponding parts of vane 1' in Figs. 6 and 8 are a', b', c', and d'.

In the form of vane 1a in which the V's have equal sides e and f, Figs. 5 and 7, the V's or flutes all point toward the apex of the cone. In the form of vane 1' of Figs. 6 and 8, while the flutes strictly do not point toward the apex, due to the inequality of sides a' and b', the ridge lines d' lie in a plane which intersects the imaginary apex of the cone. This is also true of the ridge line d of the form of vane 1a.

The purpose of the form of fluting in which the two sides of the V are unequal is to cause a rotary, spinning, motion of the shuttle in flight. This is not necessary for straight flight but is designed to meet the demands of some players.

In the ordinary feathered shuttle this spin is caused by the overlapping of the vanes of the feathers all in one direction. This is necessary in the feathered type to give a symmetrical appearance. The spinning is merely incidental.

The fluting described above is done after the stiffened vane is removed from the form indicated in Fig. 1 and before attaching to the head. A female mold grooved to the form desired is employed. This is heated and the vane placed in it. A male mold or plunger bearing V's corresponding to those in the female mold is inserted in register. The heat softens the stiffening material and the operation presses and stretches the vane outward into the grooves—ironing it into this fluted form.

I do not desire to limit the invention to any particular sizes or dimensions of the various parts of the shuttlecock as these may be changed without departing from my invention as set forth in the accompanying claims. Nor is it desired to restrict the invention to other features such as materials used, since it will be apparent that these may be varied within the scope of the invention.

I claim:

1. A shuttle for the game of badminton or the like comprising a head, and a vane consisting of a cone-shaped member of seamless tubular stiffened textile fabric secured to said head.

2. A shuttle for the game of badminton or the like comprising a head, and a vane consisting of a cone-shaped member of seamless tubular stiffened knitted fabric secured to said head.

3. A shuttle for the game of badminton and the like comprising a head and a vane or tail member attached thereto consisting of a cone-shaped member of tubular seamless stiffened textile fabric having greater density of texture near the smaller end of the seamless tubular fabric cone than toward the larger end thereof to aid in locating the center of gravity of the shuttle at the desired point at the base of the head.

4. A shuttle according to claim 3 in which said seamless cone of fabric has constituent strands in closer relation providing smaller interstices near the smaller end of the cone than toward the larger end thereof.

5. A shuttle for the game of badminton and the like comprising a head and a vane or tail member attached thereto consisting of a cone-shaped member of tubular seamless fabric having greater density of texture with smaller interstices near the smaller end of the seamless tubular fabric cone than toward the larger end.

- thereof, the wall of said cone being also provided with a stiffening material in greater quantity near the smaller end of the cone than toward the larger end thereof to aid in locating 5 the center of gravity of the shuttle at the desired point at the base of the head.
6. A shuttle for the game of badminton and the like comprising a head and a featherless, seamless vane or tail member attached thereto 10 of cone-like form and of tubular fabric having interstices smaller near the base of the head than toward the larger end of the seamless fabric cone to make the smaller end of the vane heavier than the larger end and thus to aid in 15 locating the center of gravity at the desired point at the base of the head, said cone being provided with a stiffening material, said stiffening material fixing said fabric in cone-like form with the interstices varying in size as aforesaid.
- 20 7. A shuttle for the game of badminton and the like having a head provided with a covering of colloidal material as a substitute for the usual leather covering.
8. A shuttle for the game of badminton or the 25 like comprising a vane consisting of seamless tubular textile fabric stretched to cone shape and stiffened and fixed in cone shape by a colloidal coating, and a head secured to said vane and provided with an outer envelope of colloidal 30 coating material.
9. A shuttle according to claim 8 in which said colloidal coating material comprises rubber, plasticized glue, plasticized pyroxylin, or the like colloidal material, and includes a suitable white 35 pigment such as sulphide or oxide of zinc or oxide titanium.
10. A shuttle for the game of badminton and the like having a head provided with a composition envelope as a substitute for the usual 40 leather covering, said composition envelope including colloidal material.
11. A shuttle according to claim 10 in which said composition envelope includes fibrous material.
- 45 12. A shuttle according to claim 10, in which said envelope comprises a fabric stockinet pulled over the head and impregnated and covered with said colloidal material.
13. The herein-described method of making a 50 shuttle for the game of badminton and the like, consisting in applying over a conical form, a tube of fabric, stretching it both longitudinally and circumferentially over the larger portion of the conical form, and fitting it smoothly to a 55 smaller portion of the conical form, applying a stiffening material to the cone of fabric upon the conical form, removing the apex end of the fabric cone, removing the stiffened fabric cone from the form, and securing the open small end 60 of the cone to a head to form the shuttle.
14. The method of claim 13, including applying the stiffening material to the cone of fabric upon the conical form in greater quantity near the smaller end of the cone of fabric than toward the larger end thereof.
- 65 15. The herein-described method of making a shuttle for the game of badminton and the like, consisting in applying a tube of fabric to a conical form to fit a smaller portion of the conical 70 form and stretching over the larger portion of the conical form, dipping the cone of fabric on the conical form into a stiffening solution for the full length of the cone of fabric to rigidify said fabric in conical shape, withdrawing it 75 from said liquid, dipping the cone of fabric on
- the conical form smaller end first into a preferably thicker stiffening solution for less than the full length of the cone of fabric before the previous coating is dry to produce a greater thickness of stiffening coating near the smaller end 80 of the cone of fabric than toward the larger end thereof, removing the apex end of the fabric cone removing the stiffened fabric cone from the form, and securing the open small end of the same to a head to form the shuttle.
- 85 16. The herein-described method of making a shuttle for the game of badminton and the like, consisting in forming a conical tube of fabric, dipping the cone of fabric, smaller end first, into a coating or stiffening solution, withdrawing it from said liquid, and before the applied coating is dry dipping the cone of fabric, smaller end first, into a preferably thicker solution of coating or stiffening material for less than the previously 90 dipped length of the cone of fabric, to produce a greater thickness of stiffening coating near the smaller end of the cone of fabric than toward the larger end thereof.
- 95 17. The method of claim 13 in which the rim of the small end of the stiffened vane is softened by a suitable solvent, and fitted to the head, and glued or cemented thereto.
- 100 18. A shuttle for the game of badminton or the like comprising a cylindrical head provided at its rear side with a reduced shank forming a shoulder, and a vane of hollow conical formation having its smaller end open, said end of the vane being smaller diametrically than the larger diameter of the head, said end of the vane surrounding the shank and contacting with the rear side of the head at the shoulder, and said end of the vane being secured to said shank.
- 105 19. A shuttle for the game of badminton or the like comprising a head, a vane of hollow conical formation secured at its smaller end to the head, the wall of the vane toward the larger end thereof being fluted in zig-zag formation to provide V-shaped outward prominences or ridges extending longitudinally of the larger end of the vane and becoming narrower and smaller until they merge into the smooth wall of the vane at a point within said larger end, said V-shaped flutings tending to maintain symmetry and to increase air resistance.
- 110 120 20. A shuttle according to claim 19 in which said V-shaped flutings have unequal sides to cause a rotary spinning motion of the shuttle when in flight.
- 115 125 21. The herein-described method of making a shuttle for the game of badminton and the like, consisting in applying over a conical form a tube of fabric, stretching it over the larger portion of the conical form, and fitting it smoothly to a smaller portion of the conical form, closing an end of the tube beyond the smaller end of the conical form, drawing the other end of the tube inwardly over the larger end of the conical form, applying a stiffening to the cone of fabric upon the conical form, severing the ends of the 130 cone of fabric upon the conical form in alignment with the ends of the form, removing the stiffened fabric cone from the form, and securing the smaller end of the same to a head to form the shuttle.
- 135 140 22. A shuttle according to claim 5 in which said stiffening material comprises colloidal coating material.
- 145 ADDISON T. SAUNDERS.

CERTIFICATE OF CORRECTION.

Patent No. 1,924,259.

August 29, 1933.

ADDISON T. SAUNDERS.

It is hereby certified that the name of the assignee in the above numbered patent was erroneously described and specified as "A. G. SPAULDING & BROS." whereas said name should have been described and specified as "A. G. SPALDING & BROS." as shown by the records of assignments in this office; and that the said Letters Patent should be read with this correction therein that the same may conform to the record of the case in the Patent Office.

Signed and sealed this 26th day of September, A. D. 1933.
